2,417,403

COOLING AND LUBRICATING MEANS FOR
SEWING MACHINESSydney Zonis, Bridgeport, Conn., assignor to The
Singer Manufacturing Company, Elizabeth,
N. J., a corporation of New Jersey

Application September 6, 1944, Serial No. 552,826

6 Claims. (Cl. 112—256)

1

This invention relates to sewing machines and has for its primary object to provide improved means for cooling and lubricating a bearing surface thereof.

More specifically, the present invention has for an object to provide improved means for supplying a stream of air, or of oil-laden air, to the interengaging surfaces of a sewing machine rotary hook and its thread-carrier.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings:

Figure 1 is a vertical section taken through a portion of a sewing machine having my invention embodied therein.

Figure 2 is an enlarged sectional view of the injector used for atomizing the oil and for injecting it into the bore of the hook-shaft.

In the embodiment of the invention selected for illustration, my improved lubricating and cooling expedient is shown embodied in a sewing machine having a frame including a bed 10 and a bracket-arm standard 11. The bed 10 is formed with depending lugs 12 and 13 supporting bearings 14 and 15 in which a hook-shaft 16 is journaled for rotary movement.

The shaft 16 carries a rotary hook 17 having a raceway 18 which receives the bearing-rib 19 of a stationary thread-carrier 20. Fixed to the end of shaft 16 opposite the hook 17 is a pulley 21 which is driven by a belt 22 in the usual and well known manner. The shaft 16 is formed with an axial bore 23 which is connected by a conduit 24 in the hook-body to the raceway 18 in the hook. Preferably, a plurality of equally spaced conduits connect the bore 23 in the shaft 16 to the hook-raceway so that a plurality of streams of air or of oil-laden air may be forced into the raceway throughout its circumference.

The standard 11 is externally provided with superposed cup-shaped chambers 26 and 27 closed by a transparent cover-plate 28. An aperture 28' is formed in the cover-plate 28 so as to provide an air inlet into the chamber 27. Located within the upper chamber or oil-reservoir 26 is a plate 29 which is preferably painted white. The plate 29 is arranged parallel to the transparent cover-plate 28 and is provided with upper and lower

2

holes 30, 31. The plate 29 acts as a background so that the quantity of oil in the chamber 26 can readily be ascertained at a glance.

An opening connects the chamber 26 with the lower chamber 27, and screwed into the opening is a valve-seat member 32. A needle-valve stem 33, urged downwardly by a spring 34, cooperates with the valve-seat of the member 32 to control the flow of oil from the reservoir 26 to the chamber 27. The valve-stem 33 extends through an adjustable bushing 35 which is threaded into the top wall of the chamber 26, and fixed to the upper end of the valve-stem is a cam-lever 36. It will be obvious that, by adjustment of the screw 35, the flow of oil from the chamber or reservoir 26 to the chamber 27 may be accurately controlled and that, when no oil is desired, the cam-lever 36 may be shifted so that the spring 34 will urge the stem 33 into contact with the valve-seat member 32 to close the valve.

Screwed into the lower wall of the chamber 27 is a pipe-fitting 38 which is connected by a short pipe 39 to a T pipe-fitting 40. Threaded into one limb of the T 40 is a tube 41 of which the free end extends into and therefore communicates with the bore 23 in the hook-shaft 16. Located within the tube 41 is a sleeve-member 42 longitudinally formed with two connected and successively larger bores 44, 43 which serve as expansion chambers. Extending into the smaller bore 44 is the tip end of a cone-shaped nozzle 45 which is soldered or otherwise secured to one end of the "Street" elbow 46. Threaded into the other end of the elbow is a pipe 47 which is connected through a valve 48 to any suitable source of compressed air. The compressed air may come from a rotary pump or from a central compressor through pipe lines.

My improved hook cooling and lubricating device operates as follows: When the valve 48 is opened, compressed air is injected by the cone-shaped nozzle 45 into the chamber 44. The expansion of the air in the chambers 44 and 43 produces a suction in the chamber 27 and this suction draws air through the aperture 28' which air combines with the oil which is fed from the reservoir 26 and carries it into the air stream directly in front of the nozzle 45. The oil is atomized by the impact of the air stream and is injected through the tube 41 into the bore 23 in the hook-shaft 16. The oil-laden air, or oil mist, then travels under pressure through the longitudinal bore 23 and connecting conduit or conduits 24 to the raceway 18 in the hook, where it is projected against the bearing rib 18 of the

thread-carrier for the purpose of lubricating and cooling the bearing rib.

It will be understood that the oil-supply may be stopped at any time by simply shifting the cam-lever 36 and that when the oil-supply is shut off, only air under pressure will be delivered to the raceway of the hook. This is a highly desirable feature, for in stitching some types of delicate materials, it is undesirable to lubricate the raceway due to staining of the materials by the oil. Furthermore, by delivering air at a plurality of points judiciously selected circumferentially of the raceway, there will be produced a cushioning effect upon the thread-carrier bearing rib which minimizes heating tendencies.

I have shown the oil reservoir located above the injector but it is obvious that it may be located below the injector and the suction created by the injector may be utilized to elevate the oil.

It will be understood that my invention is not limited to the specific embodiment shown and that various other deviations may be made therefrom without departing from the spirit and scope of the following claims.

Having thus set forth the nature of the invention, what I claim herein is:

1. A sewing machine having, in combination, a rotary hook shaft formed with a longitudinal bore, a hook carried by said shaft and having a raceway, said hook being provided with a conduit connecting the bore in the shaft with the raceway, a thread-carrier journaled in said raceway, an air-supply line, and means for injecting a stream of air into the bore in said shaft for delivery through said conduit to said raceway.

2. A sewing machine having, in combination, a rotary hook shaft formed with a longitudinal bore, a hook carried by said shaft and having a raceway, said hook being provided with a conduit connecting the bore in the shaft to the raceway, a thread-carrier journaled in said raceway, and means for injecting a mixture of air and oil into the bore in said shaft for delivery through said conduit to said raceway.

3. A sewing machine having, in combination, 45 a bed, a rotary hook-shaft located below said bed and having a longitudinal bore, a rotary hook carried by said shaft and formed with a raceway, said hook being provided with a conduit leading from the bore in said shaft to the raceway, a thread-carrier journaled in said hook, an air-supply line, means for directing a stream of air into the bore in said shaft for delivery to said

raceway, an oil-reservoir, a chamber beneath said reservoir having an air inlet and means for feeding oil from said reservoir and air from said chamber into said stream of air.

5. A sewing machine having, in combination, a bed, a rotary hook-shaft located below said bed and having a longitudinal bore, a rotary hook carried by said shaft and formed with a raceway, said hook being provided with a conduit leading from the bore in said shaft to the raceway, a thread-carrier journaled in said hook, an air-supply line, means for directing a stream of air into the bore in said shaft for delivery to said raceway, an oil-reservoir, means for feeding oil from said reservoir into said stream of air, and a shut-off under control of the operator for stopping the feeding of the oil, whereby only a stream of air is supplied to the raceway of the hook.

10. A sewing machine having, in combination, a bed, a rotary hook-shaft located below said bed and having a longitudinal bore, a rotary hook carried by said shaft and formed with a raceway, said hook being provided with a conduit leading from the bore in said shaft to the raceway, a thread-carrier journaled in said hook, an air-supply line, means for directing a stream of air into the bore in said shaft for delivery to said raceway, an oil-reservoir, means for feeding oil from said reservoir into said stream of air, and a shut-off under control of the operator for stopping the feeding of the oil, whereby only a stream of air is supplied to the raceway of the hook.

15. A sewing machine having, in combination, a bed, a rotary hook-shaft located below said bed and having a longitudinal bore, a rotary hook carried by said shaft and formed with a raceway, said hook being provided with a conduit leading from the bore in said shaft to the raceway, a thread-carrier journaled in said hook, an air-supply line, means for directing a stream of air into the bore in said shaft for delivery to said raceway, an oil-reservoir, means for feeding oil from said reservoir into said stream of air, and a shut-off under control of the operator for stopping the feeding of the oil, whereby only a stream of air is supplied to the raceway of the hook.

20. A sewing machine having, in combination, a bed, a rotary hook-shaft located below said bed and having a longitudinal bore, a rotary hook carried by said shaft and formed with a raceway, said hook being provided with a conduit leading from the bore in said shaft to the raceway, a thread-carrier journaled in said hook, an air-supply line, means for directing a stream of air into the bore in said shaft for delivery to said raceway, an oil-reservoir, means for feeding oil from said reservoir into said stream of air, and a shut-off under control of the operator for stopping the feeding of the oil, whereby only a stream of air is supplied to the raceway of the hook.

25. A sewing machine having, in combination, a bed, a rotary hook-shaft located below said bed and having a longitudinal bore, a rotary hook carried by said shaft and formed with a raceway, said hook being provided with a conduit leading from the bore in said shaft to the raceway, a thread-carrier journaled in said hook, an air-supply line, means for directing a stream of air into the bore in said shaft for delivery to said raceway, an oil-reservoir, means for feeding oil from said reservoir into said stream of air, and a shut-off under control of the operator for stopping the feeding of the oil, whereby only a stream of air is supplied to the raceway of the hook.

30. A sewing machine having, in combination, a bed, a rotary hook-shaft located below said bed and having a longitudinal bore, a rotary hook carried by said shaft and formed with a raceway, said hook being provided with a conduit leading from the bore in said shaft to the raceway, a thread-carrier journaled in said hook, an air-supply line, means for directing a stream of air into the bore in said shaft for delivery to said raceway, an oil-reservoir, means for feeding oil from said reservoir into said stream of air, and a shut-off under control of the operator for stopping the feeding of the oil, whereby only a stream of air is supplied to the raceway of the hook.

35. A sewing machine having, in combination, a bed, a rotary hook-shaft located below said bed and having a longitudinal bore, a rotary hook carried by said shaft and formed with a raceway, said hook being provided with a plurality of conduits connecting the bore in said shaft to said raceway at a plurality of points spaced from each other circumferentially of the hook, a thread-carrier journaled in said raceway, and means for directing a stream of air under pressure into the bore of said shaft for delivery through said conduits to said raceway.

40. A sewing machine having, in combination, a bed, a rotary hook-shaft located below said bed and having a longitudinal bore, a rotary hook carried by said shaft and formed with a raceway, said hook being provided with a plurality of conduits connecting the bore in said shaft to said raceway at a plurality of points spaced from each other circumferentially of the hook, a thread-carrier journaled in said raceway, and means for directing a stream of air under pressure into the bore of said shaft for delivery through said conduits to said raceway.
